UNITED STATES PATENT OFFICE.

GEORGE WARNER JAQUES, OF BURTON, OHIO.

RAIL-CHAIR.

SPECIFICATION forming part of Letters Patent No. 320,791, dated June 23, 1885.

Application filed March 11, 1885. (No model.)

To all whom it may concern:

Be it known that I, GEORGE WARNER JAQUES, of Burton, Geauga county, Ohio, have invented a new and Improved Rail-Chair, of which the following is a full, clear, and exact description.

The object of my invention is to provide a new and improved rail-chair which prevents spreading and creeping of the rails, and forms good joints.

The invention consists in the combination, with two side pieces united by a cross-piece, and having tenons on the under side, of a plate on which the side and cross piece are placed, which plate has tenons on the bottom and is placed on the sleeper, bolts being passed through the sleeper, the plate, and the side pieces.

Reference is to be had to the accompanying drawings, forming part of this specification, in which similar letters of reference indicate corresponding parts in all the figures.

Figure 1 is a perspective view of my improved rail-chair, showing it applied. Fig. 2 is a top perspective view of the chair. Fig. 3 is a perspective bottom view of the same. Fig. 4 is a perspective view of the under side of the bottom plate. Fig. 5 is a top perspective view of the same. Fig. 6 is a cross-sectional view of the rail and an end view of the chair.

The chair is formed of two side pieces, A, having their inner sides curved and shaped to fit snugly against the sides of the rail, which side pieces are united at the middle by a cross-piece, B, extending from top to bottom, and having its top shaped the same as the head of rail, so that the heads of the rail and the top of the cross-piece B will form one continuity, as shown in Fig. 1. The recesses between the plates or pieces A are so shaped that an end of a rail, C, can be passed in between them, the ends of the rails abutting against the ends of the cross-piece B. The outside piece, A, is slightly higher than the inside piece, to form a flange for carrying the wheel over the joint.

From the under side of the cross-piece B a tenon, D, projects downward, and from the

under side of each side piece, A, a short tenon 5 or stud, E, projects at each end.

An aperture, F, is formed in the lower part of each side piece, A, at the middle.

A bottom plate, G, is provided with a central aperture, H, for the tenon D, with four 5 corner apertures, H, for the tenon E, and with two apertures, J—one at each side edge—which correspond with the apertures F in the pieces A.

A tenon, K, is formed on the under side of 6 the plate G at each corner.

The plate G is placed upon the sleeper or tie L, the tenons K passing into apertures in the top of the sleeper. The pieces A B are placed on the plate G, the tenon D passing 6 into the central aperture, H, and the tenons E into the corner apertures, H, and the bolts M are passed up through the apertures J and F, and then nuts N are secured on the upper ends of the bolts and drawn up tight, whereby 7 the rail-chair is clamped securely on the sleeper or tie.

The nuts on the lower ends of the bolts M are countersunk in the sleepers, and elastic washers M' are placed under the nuts on the 7 upper ends of the said bolts M.

The chair cannot creep or give laterally. It holds the rail securely, forms an even joint, and is safe.

The chair is made of cast-iron or steel. 8

The side pieces, A, fit against the under side of the rail.

Having thus described my invention, I claim as new and desire to secure by Letters Patent—

1. In a rail-chair, the combination, with 8, the side pieces, A, united by the cross-piece B, and provided with the tenons D E, and the plate G, having apertures for the tenons, and also having tenons K on its under side, of the bolts M, for holding the chair on the sleeper 90 L, the nuts on the lower ends of the bolts being countersunk in the under side of the sleeper, and of elastic washers, and iron washers, and nuts on the upper ends of the bolts, substantially as herein shown and described. 9:

2. In a rail-chair, the combination, with the side pieces, A, united by a cross-piece, B, and provided with the tenons D E, of the plate

G, having apertures for the tenons, and also having tenons K on its under side, substantially as herein shown and described.

3. In a rail-chair, the combination, with the side pieces, A, united by a cross-piece, B, and provided with apertures F, and the tenons D and E, of the plate G, having apertures H J, and of the bolts M, passed through

the sleeper and through the bottom parts of the pieces A, substantially as herein shown to and described.

GEORGE WARNER JAQUES.
